Specification for Design.

Patented Aug. 30, 1921.

Application filed May 23, 1921. Serial No. 471,987. Term of patent 14 years.

To all whom it may concern:

Be it known that I, ALFRED P. MORGAN, a citizen of the United States, residing in the town of Montclair, county of Essex, and State of New Jersey, have invented a new, original, and ornamental Design for an Instrument-Mount for Radiopanel, of which the following is a specification, reference being had to the accompanying drawings, forming a part thereof, in which—

Figure 1 is a perspective plan view of the top of the instrument mount; Fig. 2 is a like view of the bottom, and Fig. 3 is a view in elevation, part being broken away to show a detail of the design.

I claim:

The ornamental design for an instrument-mount for radiopanel, as shown.

ALFRED P. MORGAN.
